UNITED STATES PATENT OFFICE.

SAMUEL F. MILLIRON AND JACOB PREISS, OF BALTIMORE, MARYLAND.

DESIGN FOR AN ANTIRATTLES FOR WHIPS.

SPECIFICATION forming part of Design No. 22,833, dated October 10, 1893.

Application filed August 11, 1893. Serial No. 482,942. Term of patent 3½ years.

To all whom it may concern:

Be it known that we, SAMUEL F. MILLIRON and JACOB PREISS, citizens of the United States, residing at Baltimore, in the State of Maryland, have invented a new and original Design for an Antirattler for Whips, of which the following is a specification.

The design is shown in the accompanying drawings, in which—

10 Figure 1 is a perspective view of the anti-rattler. Fig. 2 is an edge view of the same. A circular collar or hub, *a*, has a round hole, *b*, and flat short fingers or tangs, *c*, radiate from the exterior of the hub; said tangs 15 are of uniform length and have straight ra-

dial edges which form V-shaped notches between adjoining tangs; and the two ends, *a'*, of the collar or hub project at opposite sides beyond the plane of the tangs.

What we claim is—

20 The design for an anti-rattler for whips as herein shown and described.

In testimony whereof we affix our signatures in the presence of two witnesses.

SAMUEL F. MILLIRON.
JACOB PREISS.

Witnesses:

L. ISMY VAN HORN,
C. C. HINES.
